UNITED STATES PATENT OFFICE.

MAXIMILIAN JOSEPH HELMES, OF NEW YORK, N. Y., ASSIGNOR TO Q & C COMPANY, OF NEW YORK, N. Y., A CORPORATION OF MAINE.

DERAIL.

Application filed April 8, 1927. Serial No. 181,922.

This invention is an improvement in derailing devices and relates particularly to that class of derail in which the movable derailing block is operated by connections from a switch stand whereby it is moved from a lowered position at one side of the rail to an operating position upon the rail and vice versa.

An important feature of the present invention consists of an improved structure and arrangement of the parts providing for an improved mode of operation whereby the derailing block as it approaches the operating position upon the rail will have a movement which closely approximates a vertical movement as a result of which it will effect proper bearing engagement with rail sections of differing heights. To effect the desired movement I have provided that the standard and derailing block members shall have operating bearing surfaces at the forward or rail end of the device that are inclined and angularly disposed to produce a lifting action having a substantially vertical component by reason of the shifting of the bearing points of contact both in the longitudinal and transverse planes. Other important features of my improved device comprise an improved form and design of the derailing block providing a supplemental deflecting or derailing flange positioned to be engaged by the car wheel rearward of the main deflecting flange in the event of the car wheel jumping over the latter, thereby introducing an added safety factor; further, in the provision of a base plate extension of the standard member positioned to underlie the track rail thereby allowing of more firmly securing the derailing device in position with relation to the rail and in effect as a part of the track structure.

The foregoing and other important features and advantages of my present improvements will be more fully understood by reference to the accompanying drawings wherein like reference characters are applied to the corresponding parts in the several views.

In the drawings:

Fig. 1 is a view of my improved derailing device shown in assembled position with relation to the rail and with the derailing block in its forward or operating position.

Fig. 2 is a similar view in side elevation showing the derailing block in rearward or lowered position.

Fig. 3 is a plan view thereof with portions

broken away to disclose the improved bearing arrangement.

Fig. 4 is a view thereof in rear end elevation.

Fig. 5 is a vertical, longitudinal sectional view through the housing member taken centrally thereof.

Fig. 6 is a view in rear end elevation of the derail block member, and

Fig. 7 is a view in side elevation of the block member.

In the approved embodiment of the features of my invention as here illustrated, the derail comprises the base structure comprising a single casting and a one piece derailing block member having bearing engagement with the standard and arranged to be movable thereon toward and from the rail by movement transmitted thereto by connections from a switch stand and wherein the movement imparted to the derailing block is determined by the form and arrangement of the co-acting bearing surfaces of the standard and block members. The standard or base structure as here shown comprises, as a one piece casting, the vertically positioned side walls 1, base flanges 2, extending horizontally therefrom at opposite sides for bearing engagement upon adjacent ties, forwardly extending tie plate members 3—3, positioned to underlie the track rail and provided with spike apertures to receive the usual securing spikes at the inner sides of the rails. The side walls are united at their rearward and upper portions by an inclined connecting roof wall 5, the latter affording protection to the operating connection and bearings as will be hereinafter more fully understood.

The derailing block member is indicated at 7, and is formed with the usual angularly disposed derailing flange 8, and at its under side is formed or cut away at 9, to overlie the track rail and to have shoulder engagement therewith at the side of the rail head. The derailing block member 7, has integrally formed therewith, the bearing portion or lateral extension 10, comprising a central vertical web portion 11, formed at its lower portion with opposite lateral flanges 12, and at its forward end with outwardly and downwardly projecting flange portions 13—13, and at its extreme rearward portion is formed with the apertured bearing 15, for the reception of connecting pin for connecting to suitable operating connection from a switch stand. The

bearing portion of the derailing block is provided at its opposite sides with forward and rearward bearing projections or shoulders 16 and 17, adapted to have sliding bearing engagement with bearing flanges or ways provided therefor upon the standard or base member. As here shown, the slideway bearings are formed by means of inwardly projecting flanges 18 and 19, on each of the side walls of the standard, the forwardly positioned bearing flanges 18, being arranged to be engaged by the forward bearing shoulder 16, of the block member, and the rearward bearing flanges 19, being positioned to be operatively engaged by the bearing shoulders 17, of the block. Complemental to the lower bearing flanges 18 and 19 of the standard there are provided upper inwardly projecting bearing flanges 21, in suitably spaced relation to the lower bearing flanges to provide slideways for confining the bearing projections of the derailing block to determine the sliding movement thereof.

In accordance with an improved feature of the present improvements, the slideway bearings of the standard and the co-acting bearing shoulders of the derailing block member are peculiarly formed and arranged to determine that the movement of the derailing block from its rearmost position away from the rail shall be forward and with a lifting movement to carry the derailing block proper above the rail and whereby at the extremity of the forward movement the head portion of the block will be lowered throughout a substantial movement in approximately a vertical plane. As a consequence, and as will be appreciated, the improved movement will accommodate and allow of the device being employed with rail sections of varying height and thereby effecting substantial economy in pattern equipment. To this end and as here shown, the forward bearing flanges 18, of the standard are formed with downwardly and rearwardly inclined portions 24, operative to effect the lowering of the derailing head when in rearmost position, and at their forward ends being formed with downwardly and forwardly inclined portions 25, which in addition have their bearing surface angularly disposed with respect to the longitudinal axis of the guideways. For operatively engaging therewith, the shoulder projection 16, of the derailing block, in addition to being laterally projecting, have their engaging surfaces angularly disposed with relation to the axis of the guideways whereby in the movement of the block member from extreme forward position in the rearward direction, the shoulder bearing 16, will ride upwardly on the inclined flange bearing 25, with a lateral shifting of the bearing point of contact effective to impart a vertical component to the movement of the derailing member during the initial period of its movement. The flangeway bearing

19, for operative engagement with the rear bearing lugs 17, is formed with an extended horizontal rearward portion as shown and at its extreme forward end portion is similarly formed with a downwardly and forwardly inclined bearing surface angularly disposed with relation to the axis of movement, and the derailing block bearing shoulder 17, is formed with its outer engaging surface 27, cut away to be angularly disposed with relation to the longitudinal axis of the guideways whereby at the extreme forward position the co-operative engagement between the bearing surfaces will be such as to allow lowering of the derailing block on to the rail, in conjunction with the action of the forward bearings, in close approximation to a vertical movement.

The derailing block is further designed to incorporate features of advantage over types as heretofore employed and accordingly is formed as shown, with the longitudinally extending and angularly disposed main deflecting flange 8, and provided at the entry end with the usual flange groove 29, and inclined tread surface 30. In accordance with the present improvements to the rearward of the main deflecting flange, there is provided the supplemental deflecting flange 31, positioned to be effective with a derailing movement should the wheel, by reason of its velocity, ride over the main deflecting flange 8, and accordingly there is an additional safety factor provided for.

Additional structural features of improvement as herein provided, consist in providing depending extension 33, of the side walls of the standard for bearing engagement against the sides of the ties and forward extensions 34, of the side walls, adapted to bear against the web portions of the track rails thereby determining the spaced relation of the derailing device thereto, the latter being of a contour to provide for the required clearance of rail sections of varied sizes.

The derailing block member at the rearward portion of its head portion, is formed with a downwardly curved ledge portion 35, providing a convenient hand hold for manually operating the device when desired.

I have accordingly produced an improved derailing device which in its operation will determine the movement of the derailing block with a path of movement which is such as to properly co-act with rail sections of varying sizes and is accordingly self-adjusting with relation to rails of varying height.

While I have shown and described a preferable embodiment of the features of my invention, it will be understood that varied structural modifications may be made therein without departing from the scope of the invention as defined in the appended claims.

Having described my invention, I claim:

1. A derail comprising a standard pro-

- vided with bearing surfaces and a derail member movably associated therewith and provided with co-acting bearing surfaces, said bearing surfaces effective at the extreme forward position of the derail member comprising downwardly and forwardly inclined bearing surfaces on the standard angularly disposed with relation to the path of movement of the derail member and co-acting surfaces 5
- 10 on the derail member angularly disposed to said path of movement to provide a shifting point of bearing contact and to impart a vertical component to the movement of the derail head.
- 15 2. A derail comprising a standard or base member and a derailing block member supported thereon to be slideable into and out of operative position, said members being provided with supplemental stud and slide- 20 way bearings cooperating to determine the movement of the derailing member from a lowered rearward position to an elevated position upon the track rail and said slideway bearings being formed at their forward portions with bearing surfaces arranged to be forwardly and downwardly inclined and angularly disposed with relation to the axis of movement of the derailing member and said studs being formed with engaging sur- 25 faces angularly disposed with relation to said axis whereby at the forward position of the derailing member a shifting point of bearing contact is effected to impart a vertical component to the movement thereof.
- 30 3. A derail comprising a standard or base member and a derailing block member supported thereon to be slideable into and out of operative position, said members being provided with forward and rearward coacting stud and slideway bearings, said slideway bearings being formed to determine the movement of the derailing member from a lowered rearward position to an elevated forward position upon the track rail and formed at their 35 forward portions with surfaces arranged to be forwardly and downwardly inclined in angular relation to the axis of movement of the derailing member and said studs being formed with engaging surfaces angularly disposed with relation to said axis whereby at the forward end of the movement a shifting point of bearing contact is effected to impart a vertical component to the movement of the derailing member.
- 40 4. A derail comprising a standard or base member and a derailing block member supported thereon to be slideable into and out of operative position, said members being provided with oppositely positioned forward and rearward coacting stud and slideway bearings, said slideway bearings being formed to determine the movement of the derailing member from a rearward lowered position to a forward elevated position upon the rail and 45 formed at their forward portions with sur-
- faces arranged to be forwardly and downwardly inclined in angular relation to the axis of movement of the derailing member and said studs being formed with engaging surfaces angularly disposed with relation to said axis whereby a shifting point of bearing contact is effected to impart a vertical component to the movement of the derailing member when in extreme forward position. 50
5. A derail comprising a standard and a derailing block supported thereon to be movable into and out of operative position, said standard being provided with forward and rearward slideway bearings, said slideway bearings being formed at their forward portions with surfaces arranged to be forwardly and downwardly inclined in angularly disposed relation to the axis of movement of the derailing block, said derailing member being provided with forward and rearward bearing studs positioned to engage with the slideway bearings of the standard and having engaging surfaces thereof angularly disposed with relation to the path of movement of the derailing member whereby at the extreme forward position of the latter a shifting point of bearing contact is effected to impart a vertical component to the movement of the derailing head. 55
6. A derail comprising a standard and a derailing block supported thereon to be slideable into and out of operative position, said standard being provided with opposed forward and rearward slideway bearings, said slideway bearings being formed at their forward portions with surfaces arranged to be forwardly and downwardly inclined in angularly disposed relation to the axis of movement of the derailing block, said derailing block being formed with a derailing head portion having a bearing extension provided with oppositely positioned forward and rearward bearing studs engaging the slideway bearings and said forward studs being formed with engaging surfaces angularly disposed with relation to said axis whereby a shifting point of bearing contact is effected to impart a vertical component to movement of the derailing head portion when approaching the rail. 60
7. A derail comprising a standard and a derailing block supported thereon to be slideable into and out of operative position, said standard being provided with opposed forward and rearward slideway bearings, said slideway bearings being formed at their forward portions with surfaces arranged to be forwardly and downwardly inclined in angularly disposed relation to the axis of movement of the derailing block, said standard having a base extension underlying the track rail and said derailing block being formed with a derailing head portion having a main deflecting flange and a supplemental rearward deflecting flange positioned to be engaged by a car 65

wheel should the latter ride over the main deflecting flange, said derailing block having a bearing extension provided with forward and rearward bearing studs engaging the slide-way bearings and said studs being formed with engaging faces angularly disposed with relation to said axis whereby a shifting point of bearing contact is effected to impart a vertical component to the movement of the derailing head when approaching the rail.

8. A derail comprising a standard provided with bearing surfaces and a derailing member movably associated therewith and provided

with co-acting bearing surfaces and having a head portion formed with a main deflecting flange and a supplemental deflecting flange positioned to the rearward of said main deflecting flange and positioned at the same side of the track rail as the main deflecting flange and adapted to be engaged by a wheel passing over the latter, substantially as described.

Signed at New York city in the county of New York and State of New York this 4th day of March A. D. 1927.

MAXIMILIAN JOSEPH HELMES.
